Primary Examiner — Ian Simmons*Assistant Examiner* — Carissa C Fitts*(74) Attorney, Agent, or Firm* — Gregory L. Koeller(57) **CLAIM**

We claim the ornamental design for a surgical needle device, as shown and described.

DESCRIPTION

FIG. 1 is a perspective view of a surgical needle device showing our new design.

FIG. 2 is a top view thereof; and,

FIG. 3 is a side view thereof.

The broken lines are for illustrative purposes only and form no part of the claimed design.
